UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

SHOE.

1,219,585.

Specification of Letters Patent.

Patented Mar. 20, 1917.

Original application filed October 12, 1912, Serial No. 725,476. Divided and this application filed September 23, 1914. Serial No. 863,128.

To all whom it may concern:

Be it known that I, ADAM H. PRENZEL, a citizen of the United States, residing at Halifax, in the county of Dauphin and State of Pennsylvania, have invented certain Improvements in Shoes, of which the following description, in connection with the accompanying drawings, is a specification, like reference characters on the drawings indicating like parts in the several figures.

This invention relates to shoes and is herein shown and described for purposes of illustration in its relation to shoes of the type commonly termed stitch-down shoes.

15 The manufacture of stitch-down shoes has been confined heretofore chiefly and almost entirely to the cheaper grades. This has been due largely to the very imperfect conformation of the upper to the last in shoes 20 of this type, stitch-down shoes comparing unfavorably with shoes of other types and particularly the better grades of shoes of other types not only in their original appearance but by reason of the fact that, as 25 heretofore made, stitch-down shoes have not kept their shape and appearance satisfactorily during wear.

The general object of the present invention is to provide an improved shoe of this type 30 which, without being materially more expensive to manufacture, will compare favorably in appearance and wearing qualities with the better grades of shoes of other types and which will retain its good appearance 35 and continue to fit properly even after long wear, to the end that a stitch-down shoe may be provided adapted to be manufactured not only in the better grades of children's and infants' sizes and boys' and men's sizes but 40 also in misses' and women's sizes.

More particularly the invention aims to provide a shoe the upper of which is properly conformed to the last and permanently secured exactly in final lasted position, thereby providing a neat, stylish shoe 45 which will compare favorably even with good grades of welted shoes and which will retain satisfactorily its original shape and appearance as the shoe is worn.

50 In accordance with these objects, the upper of the illustrated shoe which has a flange outturned upon the upper face of the mar-

gin of a flexible sole is permanently secured to the sole in its original lasted condition by staples of fine wire passing through the 55 upper in the vertex of the angle formed by the body of the upper and the outturned flange of the upper.

In the accompanying drawings,—

Figure 1 is a perspective view of a sole 60 which may conveniently be used in making the shoe of this invention;

Fig. 2 shows a portion of a suitable means for lasting the shoe;

Fig. 3 shows a shoe after it has been lasted 65 and before the sole has been finally secured to the upper;

Fig. 4 shows the completed shoe; and

Fig. 5 is a sectional detail showing the location of the different parts of the shoe 70 and the fastenings which unite these parts.

The upper 1 of the illustrated shoe, which, as above stated, is of the type commonly termed a stitch-down shoe, has an outturned flange 3 overlying the upper face of the margin 6 of a flexible sole indicated generally at 75 5. The upper 1 is permanently secured to the sole 5 in its original lasted condition by staples of fine wire passing through the upper 1 in the vertex of the angle 10 formed 80 by the body of the upper 1 and the outturned flange 3, the outturned flange 3 being entirely outside the line of junction, indicated at 7, of the inner face 9 of the upper 1 with the sole 5 and the line in which the 85 upper 1 is so secured by the staples to the sole 5, being, as will be also apparent from the drawings, of approximately the same 90 contour as the said line of junction of the inner face of the upper with the sole.

It will be observed that, as shown, the heads 14 of the staples lie in close proximity to and parallel to the bottom edge of the last. In this location, the staples are out of the way of the fastenings inserted in the later outsole stitching or other operation by which the sole is secured to the upper so that they may remain in the finished shoe. Thus the staples not only serve as lasting fastenings, taking the place 100 of temporary lasting fastenings, such as tacks, or taking the place of cement, which has heretofore been commonly used, and securing the upper as it is lasted exactly in

final lasted position, but also permanently secure the upper precisely in that final lasted position, insuring not only initial proper conformation of the upper to the last, but further insuring that the upper will retain that proper conformation to the last during subsequent operations on the shoe and as the shoe is worn.

As shown, the legs 16 of the staples are inclined to the face of the sole 5 and extend obliquely inwardly beneath the last 8. This not only insures that the legs of the staples will be entirely out of the way of the stitches or other fastening means subsequently employed in attaching the sole to the upper, but the legs of the staples extend into the sole 5 in directions substantially transverse to the directions of pull of the stretched upper, thus increasing the holding power of the staples, the inclination and length of the legs of the staples of the illustrated shoe being such that they do not penetrate the tread face of the sole 5. It will be seen that the described location of the staples is not only adapted to the construction of shoes in which the sole 5 to which the upper is shaped is the outer-sole, maximum holding power of the staples being secured without having the fastenings appear upon the tread face of the sole of the finished shoe, but at the same time the described construction is well adapted for a "double soled" shoe; that is, a shoe having an outer sole attached to the sole 5. It will be appreciated that, although the described construction has marked advantages including those above set forth, it is not essential either that the legs of the staples shall extend obliquely into the sole 5 or that they shall terminate in the said sole without penetrating its tread face. For example, within the scope of the invention, the legs of the staples may extend either obliquely or substantially vertically into the sole 5, either terminating in the said sole or extending through the sole and being clenched upon the outer face of the sole as is a frequent practice especially when the shoe has an outer sole attached to the sole 5.

A preferred mechanism for progressively lasting the successive portions of the shoe upper and inserting staples of fine wire in the vertex of the angle of the upper step-by-step as the shoe is lasted to secure the upper permanently in lasted position as above described, is disclosed and claimed in my co-pending application, on which application Letters Patent No. 1,117,087 were granted November 10, 1914, for improvements in machines for lasting boots and shoes. A portion of this machine is shown in Fig. 2, the parts there shown being relatively movable, as fully set forth in said Letters Patent, to effect the forcing of the successive portions of the upper step-by-step

into the angle between the last and the sole margin and the securing of said portions of the upper in lasted position.

To provide support for the upper upon the inside of the shoe so that the upper will not tend to break away from the welt and thus leave an undesirable crack, the sole 5 may be shouldered to provide a raised portion 2 which does not extend beyond the edge of the last and affords the desired support for the upper. Such a sole is shown in Fig. 1 and may be made in various ways, as, for example, by the process described in my co-pending application, on which application Letters Patent No. 1,147,187 were granted July 20, 1915. According to this construction, the raised portion 2 of the sole 5 presents an outline such that its edge 4 lies flush with the bottom edge of the last 8 when the sole is placed on the last, the margin 6 projecting beyond the bottom edge of the last and having the flange 3 of the upper outturned upon the upper face thereof. Such support for the upper may also be provided by an insole which extends only to the edge of the last. When a shouldered sole such as that shown in Fig. 1 is utilized, it will be observed that the staples pass through the angle 10 of the upper into the sole in the angle 12 between the shoulder 4 and the sole margin 6. It will be understood, however, that in its broader aspects the invention comprehends a shoe in which the projecting margin 6 of the sole 5 lies flush with the upper portion of the remainder of the sole. In that case, the staples pass through the angle 10 of the upper into the angle between the last 8 and the sole margin 6. As shown in Fig. 5, the upper of the finished shoe may be trimmed back from the edge of the sole a short distance in order that it may not interfere with finishing the edge of the sole, and the shoe may have a welt 18 superposed upon the outturned flange 3 of the upper, the welt being of a width sufficient to extend to the edge of the sole and being preferably thicker upon its outer edge than upon its inner edge so that it will reach down over the edge of the outturned flange 3 of the upper in contact with the upper face of the sole margin 6, thereby closing up any gap which might be caused by interposition of the upper between the welt and sole and providing a tight edge which may be finished readily in the succeeding edge finishing operations, the welt 18 being secured to the sole by stitches 20 which also pass through the upper, as shown in Fig. 5.

The novel process of making shoes involved in the production of the shoe of the present invention is not claimed herein but is made the subject-matter of my co-pending application, on which Letters Patent No. 1,117,086 were granted November 10, 1914.

1914, of which application the present application is a division.

Having described my invention, what I claim as new and desire to secure by Letters

5 Patent of the United States is:—

1. A stitch-down shoe comprising a flexible sole, and an upper having a flange outturned upon the upper face of the sole margin, the upper being secured to the sole in 10 its original lasted condition by staples of fine wire passing through the upper in the vertex of the angle formed by the body of the upper and said outturned flange, and said outturned flange being entirely outside the 15 line of junction of the inner face of the upper with the sole.
2. A stitch-down shoe comprising a flexible sole, and an upper having a flange out-

turned upon the upper face of the sole margin, the upper being secured to the sole in 20 its original lasted condition by staples of fine wire passing through the upper in the vertex of the angle formed by the body of the upper and said outturned flange, the line in which the upper is so secured being 25 of approximately the same contour as the line of junction of the inner face of the upper with the sole.

In testimony whereof I have signed my name to this specification in the presence of 30 two subscribing witnesses.

ADAM H. PRENZEL.
